UNITED STATES PATENT OFFICE

GEORGE W. MOORE, OF LONG BEACH, CALIFORNIA, ASSIGNOR TO R. E. MOORE, OF
PIEDMONT, CALIFORNIA

METHOD OF MAKING WELDLESS ELEVATOR LINKS

Application filed November 18, 1927. Serial No. 234,228.

An object of my invention is to provide a novel method of forming weldless elevator links whereby a link is provided which will not readily break under severe strain, and which is less expensive to manufacture.

Another object of my invention is to provide a weldless link which is formed with a very few operations, such operations being simple and quickly performed.

Other objects, advantages, and features of invention may appear in the accompanying drawings, the subjoined detailed descriptions, and the appended claims.

In the drawing—
15 Fig. 1, is a side elevation of the bar from which the link is made.

Fig. 2, is a side elevation of the bar in the next stage of manufacture.

Fig. 3, is a side elevation of the bar in the 20 third step of completion.

Fig. 4, is a plan view of the completed bar.

Fig. 5, is a side elevation of the same.

Fig. 6, is a side elevation of my links in position on an elevator.

25 Referring more particularly to the drawing, my weldless link is formed in a series of steps starting with a bar 1, of substantially uniform diameter through its length. This bar being then moved through the rollers forming the structure as shown in Fig.

30 2, consists of a central circular cross section 2, the ends 3, 4, being of substantially the same diameter as the bar 1, with which I start. During this rolling operation, the

35 bar is elongated to the required length, which length varies from 6 feet to 8 feet, more or less. The rolling operation is so controlled that each bar is made exactly the same length; this insures a uniform strain on the two links

40 which support the elevator.

The next step consists in flattening the ends 3, 4, as shown at 5, 6. The central section 2 remains undisturbed. The next operation consists in cutting the openings 45 7, 8, to form the eyes 9, 10. The opening 7, which extends over the elevator lugs is smaller in size than the opening 8, which is engaged by the block hook, that is the opening 7, is smaller in dimension along the longitudinal axis of the link than the opening 8.

The upper end of the eye 10, is flattened as at 11, and is bent upwardly at an angle. The purpose of the flattening is to provide more metal along the line of greatest strain, and the bending is to enable the two links to fit 55 more closely together, when in use on an elevator as shown in Fig. 6.

The central section 2, tapers gradually outwardly into the eyes 9, 10, so that no abrupt angles are formed, across which a break can 60 occur. The gradual tapering distributes the strain more equally and there is less likelihood of a fracture occurring at the point where the eyes and the central section come together.

It is obvious that the above described method can be accomplished by forging the bar into shape as well as by rolling the same, and also it may be desirable to make the end 3, slightly smaller in diameter than the end 4, by reason of the fact that the eye 9, is 70 smaller than the eye 10.

When the links are in actual use, one of the operators stands a considerable distance above the floor of the derrick on a specially provided platform, and as the elevator passes him, he reaches out and grasps the links to pull the pipe over into the rack. To provide a convenient hand grasp, a pair of loops 12, 12, are secured at either end of the link by 80 either welding or other suitable processes, and a cable is then secured in the loops and extends between them thus forming a hand grasp for the operator.

In the rolling operation, and in the cutting 85 of the eyes 9, 10, it is desirable that the cross sectional area of the central section 2, be about the same as the sum of the cross sectional area of both sides of the loop, thus making all parts of the link substantially the 90 same in tensile strain.

Having described my invention, I claim:
1. A method of forming a weldless elevator link which consists in rolling a bar of uniform cross sectional diameter into a section 95 of reduced central diameter, both ends remaining the same dimension in cross section as the original bar, then flattening the ends and then cutting apertures in both ends to form eyes.

2. A method of forming a weldless elevator link which consists in rolling a bar of uniform cross sectional diameter into a section of reduced central diameter, both ends remaining the same dimension in cross section as the original rod, then flattening the ends and then cutting apertures in both ends to form eyes, the aperture in one eye being of greater longitudinal dimension than the opening in the other eye, then flattening the outer end of the longer eye and bending the flattened portion upwardly at an angle.
3. A method of forming a weldless elevator link which consists in cutting a bar into lengths less than the final length of the link, then rolling the bar to form a lesser diameter, central section, said rolling extending the bar to the length of the completed link, the ends being the same diameter as the original bar, then flattening the ends and then cutting apertures in the flattened ends to form eyes.
4. A method of forming a weldless elevator link which consists in cutting a bar into lengths less than the final length of the link, then rolling the bar to form a lesser diameter central section, said rolling extending the bar to the length of the completed link, the ends being the same diameter as the original bar, then flattening the ends and then cutting apertures in the flattened ends to form eyes, the eye sections tapering gradually into the central section and one eye being of greater longitudinal dimension than the other.

35 In testimony whereof, I affix my signature.
GEORGE W. MOORE.
